William R. Kloster, Muscatine, Iowa, assignor to Carver Foundry Products, Muscatine, Iowa, a corporation of Iowa

Filed Sept. 3, 1968, Ser. No. 13,366

Term of patent 14 years

Int. Cl. D15—99

U.S. Cl. D55—1

Fig. 2.

Fig. 3.

FIG. 1 is a side elevation view, in perspective, of a mulling arm made up of identical individual blades employing my new design, wherein portions thereof are shown in dashed lines to indicate a repetition of relationships shown in full lines for convenience of illustration;

FIG. 2 is an end elevational view of an individual blade thereof; and

FIG. 3 is an end elevational view of the same blade shown in FIG. 2 as seen from an opposite end thereof.

I claim:

The ornamental design for a mulling arm made up of identical individual blades, substantially as shown and described.
